UNITED STATES PATENT OFFICE.

JOSEPH E. KENNEDY, OF NEW YORK, N. Y.

CRUSHING AND PULVERIZING MACHINE.

1,115,838.

Specification of Letters Patent.

Patented Nov. 3, 1914.

Application filed June 12, 1912. Serial No. 703,178.

To all whom it may concern:

Be it known that I, JOSEPH E. KENNEDY, a citizen of the United States, and a resident of the borough of Manhattan, city, county, and State of New York, have invented certain new and useful Improvements in Crushing and Pulverizing Machines, of which the following is a specification.

10 My invention relates to the type of crushing and pulverizing mechanism in which a gyratory shaft is journaled at its lower extremity in an eccentric bearing seated in a rotatable sleeve, as in my concurrent applications No. 387,067, filed August 5th, 1907 and No. 681,611, filed March 4th 1912.

20 My present improvements concern the means employed for insuring the rotation of the eccentric bearing with the sleeve in which it is seated in such manner as to allow the eccentric bearing to adapt itself to the inclination of the gyratory shaft,—the object being to obviate as far as possible wear between the contacting surfaces of the interlocking parts by which the eccentric bearing and rotatable sleeve are coupled together, as hereinafter fully set forth.

25 In the accompanying drawings, Figure 1, is a central vertical sectional elevation of the lower portion of a gyratory crusher of the type to which my invention is applicable; Fig. 2, is a horizontal section taken upon plane of line 2—2 Fig. 1; Fig. 3, shows the several details of the coupling pin and slot 35 upon a larger scale. Fig. 4, shows an alternative or modified construction of interlocking parts.

30 In general construction and operation the apparatus is essentially the same as heretofore known and used, A, representing the gyratory shaft upon the upper part of which the usual truncated conical crusher head is supported in an oppositely inclined conical crushing chamber.

45 The lower portion of the gyratory shaft A, is journaled in the bore b, of the eccentric bearing B, which is formed with a convex peripheral surface b', seated in a corresponding concavity s, in the rotatable sleeve S, 50 to which the driving gear d, is secured,—said driving gear d, being rotated by the pinion p, on the power shaft P.

55 In order to insure the rotation of the eccentric bearing B, with the sleeve S, and at the same time to allow it to conform to the inclination of the longitudinal axis of the

gyratory shaft S, it is necessary to couple the eccentric bearing B, and the sleeve S, together by means which will allow the convex peripheral surface b', of the eccentric bearing B, to rock laterally on the concave seat s, of the sleeve S, and in order to accomplish this in a simple and effective manner I provide on one part a coupling pin c, the protruding elongated head c', of which 60 engages with a side wall of a longitudinal recess r, in the other part.

65 By preference I form the longitudinal recess r, in the sleeve S, opening into the concave s, and mount the shank of the pin c, in a socket b², formed for its reception in the eccentric bearing B, as shown in the accompanying drawings, although it is obvious that the alternative arrangement may be resorted to without departing from the 70 spirit and intent of my invention in this respect. That is to say as an equivalent mechanical expedient the longitudinal recess r, may be formed in the eccentric bearing B, and the coupling pin c, be mounted in the 75 sleeve if desired with like result as shown in Fig. 4. The important feature in this connection is the formation of the coupling pin c, with an elongate head c', affording an 80 extensive bearing surface for contact with a side of the longitudinal slot, thereby 85 equalizing and distributing the wear, and lengthening the life and utility of the bearing. In other words I counteract the tendency of the head of the coupling pin to 90 augment frictional resistance, and even eventually render the ball and socket joint 95 inoperative, by wearing a seat for itself in the opposed wall surface of the longitudinal coupling slot.

95 What I claim as my invention and desire to secure by Letters Patent is,

1. In a crushing mechanism of the character designated, the combination of a gyratory shaft, means for supporting the same, 100 an eccentric bearing for the lower portion of said shaft, said eccentric bearing consisting of a plurality of members, one member having a convex peripheral surface, another of said members being a rotatable eccentric sleeve formed with a concavity in which said first named member is seated, and also formed with a longitudinal recess in said concave seat, a coupling pin movable in a socket formed for its reception in said 105 first named member, said pin being formed with a head protruding into the longitudinal

recess in the sleeve, said head having a bearing surface contacting with the side thereof to prevent said pin from turning in said recess, whereby the positive rotation of the 5 first named member with the sleeve is insured while permitting the bearing to adapt itself axially to the inclination of the shaft, and means for rotating said sleeve.

2. In crushing mechanism of the character 10 designated, the combination of a gyratory shaft, means for supporting the same, an eccentric bearing for the lower portion of said shaft in which said shaft is movable, said eccentric bearing consisting of a plurality of members one member having a convex peripheral surface, another of said members being a rotatable eccentric sleeve formed with a concavity in which said first 15 named member is seated, and means for coupling said first named member and said sleeve together in such manner that they will rotate together while admitting the first named member to adapt itself to the axial inclination of the gyratory shaft, said means 20 consisting of a coupling pin mounted on one member and formed with a non-rotative head protruding into a longitudinal recess in the other member and having an extensive bearing surface contacting with the longitudinal 25 bearing surface of the recess in the sleeve, whereby the first named member is 30

permitted to adapt itself axially to the inclination of the shaft while rotating positively with the sleeve, and means for rotating said sleeve.

3. In crushing mechanism of the character 35 designated, the combination of a gyratory shaft, means for supporting the same, an eccentric bearing for the lower portion of said shaft in which said shaft is movable, said eccentric bearing consisting of a plurality of members one member having a convex peripheral surface, another of said members being a rotatable eccentric sleeve formed with a concavity in which said first 40 named member is seated, and means for coupling said first named member and said sleeve together in such manner that they will rotate together while admitting the first named member to adapt itself to the axial inclination of the gyratory shaft, said means 45 consisting of a coupling pin mounted on one member and formed with a non-rotative head protruding into a longitudinal recess in the other member and having an extensive bearing surface contacting with the longitudinal bearing surface of the recess.
